CLAIM

We claim the ornamental design for an adhesive bandage with decorated pad, as shown and described.

DESCRIPTION

FIG. 1 is a top perspective view of the present invention; FIG. 2 is a top view of the adhesive bandage with decorated pad depicted in FIG. 1;

FIG. 3 is a left side view of the adhesive bandage with decorated pad depicted in FIG. 1;

FIG. 4 is a bottom view of the adhesive bandage with decorated pad depicted in FIG. 1;

FIG. 5 is a right side view of the adhesive bandage with decorated pad depicted in FIG. 1;

FIG. 6 is a front side view of the adhesive bandage with decorated pad depicted in FIG. 1;

FIG. 7 is a back side view of the adhesive bandage with decorated pad depicted in FIG. 1;

FIG. 8 is a top perspective view of a second embodiment of the present invention;

FIG. 9 is a top view of the adhesive bandage with decorated pad depicted in FIG. 8;

FIG. 10 is a left side view of the adhesive bandage with decorated pad depicted in FIG. 8;

FIG. 11 is a bottom view of the adhesive bandage with decorated pad depicted in FIG. 8;

FIG. 12 is a right side view of the adhesive bandage with decorated pad depicted in FIG. 8;

FIG. 13 is a front side view of the adhesive bandage with decorated pad depicted in FIG. 8;

FIG. 14 is a back side view of the adhesive bandage with decorated pad depicted in FIG. 8;

FIG. 15 is a top perspective view of a third embodiment of the present invention;

FIG. 16 is a top view of the adhesive bandage with decorated pad depicted in FIG. 15;

FIG. 17 is a left side view of the adhesive bandage with decorated pad depicted in FIG. 15;

FIG. 18 is a bottom view of the adhesive bandage with decorated pad depicted in FIG. 15;

FIG. 19 is a right side view of the adhesive bandage with decorated pad depicted in FIG. 15;

FIG. 20 is a front side view of the adhesive bandage with decorated pad depicted in FIG. 15;

FIG. 21 is a back side view of the adhesive bandage with decorated pad depicted in FIG. 15;

FIG. 22 is a top perspective view of a fourth embodiment of the present invention;

FIG. 23 is a top view of the adhesive bandage with decorated pad depicted in FIG. 22;

FIG. 24 is a left side view of the adhesive bandage with decorated pad depicted in FIG. 22;

FIG. 25 is a bottom view of the adhesive bandage with decorated pad depicted in FIG. 22;

FIG. 26 is a right side view of the adhesive bandage with decorated pad depicted in FIG. 22;

FIG. 27 is a front side view of the adhesive bandage with decorated pad depicted in FIG. 22;

FIG. 28 is a back side view of the adhesive bandage with decorated pad depicted in FIG. 22;

FIG. 29 is a top perspective view of a fifth embodiment of the present invention;

FIG. 30 is a top view of the adhesive bandage with decorated pad depicted in FIG. 29;

FIG. 31 is a left side view of the adhesive bandage with decorated pad depicted in FIG. 29;

FIG. 32 is a bottom view of the adhesive bandage with decorated pad depicted in FIG. 29;

FIG. 33 is a right side view of the adhesive bandage with decorated pad depicted in FIG. 29;

FIG. 34 is a front side view of the adhesive bandage with decorated pad depicted in FIG. 29;

FIG. 35 is a back side view of the adhesive bandage with decorated pad depicted in FIG. 29;

FIG. 36 is a top perspective view of a sixth embodiment of the present invention;

FIG. 37 is a top view of the adhesive bandage with decorated pad depicted in FIG. 36;

FIG. 38 is a left side view of the adhesive bandage with decorated pad depicted in FIG. 37;

FIG. 39 is a bottom view of the adhesive bandage with decorated pad depicted in FIG. 38;

FIG. 40 is a right side view of the adhesive bandage with decorated pad depicted in FIG. 39;

FIG. 41 is a front side view of the adhesive bandage with decorated pad depicted in FIG. 40; and,

FIG. 42 is a back side view of the adhesive bandage with decorated pad depicted in FIG. 41.
